UNITED STATES PATENT OFFICE.

JOSEPH F. LAMB, OF NEW BRITAIN, CONNECTICUT, ASSIGNOR TO LANDERS, FRARY & CLARK, OF NEW BRITAIN, CONNECTICUT, A CORPORATION OF CONNECTICUT.

ELECTRICALLY-HEATED UTENSIL.

Application filed July 20, 1917. Serial No. 181,838.

To all whom it may concern:

Be it known that I, JOSEPH F. LAMB, a citizen of the United States, and a resident of New Britain, in the county of Hartford, 5 State of Connecticut, have invented certain new and useful Improvements in an Electrically-Heated Utensil, of which the following is a specification.

This invention is illustrated as embodied 10 in a waffle iron and has for its object to provide features of construction having novelty and advantage and some of which are particularly adapted for use in utensils having hinged parts.

15 In the drawings—Fig. 1 is a side elevation of a waffle iron embodying my invention. Fig. 2 is an end view thereof. Fig. 3 is a detailed perspective view on enlarged scale with parts broken away to show construction. Fig. 4 is a detailed bottom view on enlarged scale demonstrating the manner of 20 securing the legs in place.

Referring to the drawings:—*a* denotes the base and *b*, *b* legs mounted thereon to 25 support the utensil *c*. The base is slotted, or otherwise apertured, to receive tongues 3 on the legs which are bent over against the under side of the base and engaged by the bent over projections 4 formed out of the 30 base. Supported by the legs is the utensil *c* here shown as a waffle iron comprising like parts 5, 5, each of which consists of a shell 10 within which is positioned one section 11 of a waffle iron, provided at its outer 35 edges with depending lugs 12, which fit closely into the shell and are tapped to receive securing screws 13, of which there will preferably be two at each end and one on each side. To the bottom of the iron section 40 11 is secured a steel, or other metal plate 14, which holds the heating element clamped against the bottom of the iron. This plate is spaced from the bottom of the shell 10 to prevent heat radiation.

45 The two parts 5, 5, of the iron are connected together by a slip joint in order to permit of their being spaced from one another slightly when closed together. The method of connection here demonstrated 50 would comprise a hinge 15, having slotted leaves 16 and securing staples 17, whose legs are smaller than the slots 16. Staples are, of course, secured to the parts 5, 5, and permit of slight movement of the two parts 55 relative to one another.

In a hinged structure each part of which carries a heating element it is preferable to have each element independent of the other, each part being thus provided with the terminal plugs 20, 20.

60 In order to connect these plugs into the circuit I utilize a conducting wire 25, having a split end and connection plugs 27, 27 being secured to each end. This permits of connecting both plugs to the parts of the 65 utensil and of separating those parts, as when a waffle iron is open, without breaking the circuit of either part. In order to support the movable part when the iron for instance is open in order to fill or empty it, I provide 70 lateral extensions 35 from one side of each leg.

75 In accordance with the provisions of the patent statutes I have described the principle of operation of my invention, together with the apparatus which I now consider to represent the best embodiment thereof; but I desire to have it understood that the apparatus shown is only illustrative, and that the invention can be carried out by 80 other means.

I claim as my invention:

1. A waffle iron made in two parts connected together with a slip joint, each part comprising a case, a metal section mounted 85 in and secured to said case, a plate secured to the bottom of each metal section and clamped thereon, a heating element positioned between said metal section and plate.

2. In a waffle iron a base, legs mounted thereon a two part waffle iron one of which parts is mounted on said legs, the other part hinged to the upper edge of the first mentioned part, and means comprising an extension on said legs lying in a plane below 90 the level of the upper edge of said first mentioned part for supporting said hinged part in a horizontal plane when in open position.

3. An electrically heated waffle iron composed of two parts each of which comprises a sheet metal case, a waffle iron section closely fitting within each case, a clamping plate secured to the bottom of each iron section and between which and the section 10. a heating element is located, and means in each case engaging its iron section to hold it in position and spaced from the bottom of the case.

4. An electrically heated waffle iron com- 11

prising two parts, means for connecting said parts together comprising a hinge having a pair of pivotally connected leaves, each provided with a pair of elongated slots, and 5 staples going through the slots in said leaves and connected to said parts, said staples being smaller than said slots.

5. A waffle iron comprising two parts hinged together, an independent heating ele- 10 ment mounted in each part, a pair of termi-

nal plugs on each part connected with the respective heating elements, and readily detachable electrical connections associated with said plugs of each part and operable to maintain both of said elements in circuit 15 in any position of adjustment of said parts.

JOSEPH F. LAMB.
